UNITED STATES PATENT OFFICE.

JOHN SCHOLL, OF JOPLIN, MISSOURI, ASSIGNOR OF ONE-HALF TO ANNA B. BROWNS, OF MERINO, COLORADO.

GARMENT-HANGER.

No. 863,100.

Specification of Letters Patent.

Patented Aug. 13, 1907.

Application filed March 18, 1907. Serial No. 363,089.

To all whom it may concern:

Be it known that I, JOHN SCHOLL, a citizen of the United States, residing at Joplin, county of Jasper, and State of Missouri, have invented certain new and useful Improvements in Garment-Hangers, of which the following is a specification.

My invention relates to garment hangers.

The object of the present invention is the provision, in one device, of novel means for supporting a coat, vest, or jacket, hat, trousers and overcoat.

Another object of the invention is to provide a garment hanger of light, simple, inexpensive, and durable construction, made from wire, wherein means for supporting various garments are associated in a novel manner so that the different garments and head-wear are independently arranged for convenient access, the device being adaptable for attachment to a wall, door or other upright support.

The invention is set forth fully hereinafter and its novel features are recited in the appended claims.

In the accompanying drawings:—Figure 1 is a perspective view; Fig. 2 is an end elevation; and Fig. 3, a detail perspective of a modified trousers hanger.

The coat, vest or jacket hanger is made from a single piece of wire 1, bent at its center into a loop 2, and formed into lobes 3 at its ends, which are provided with loops or coils 4.

The numeral 5 designates a separate wire which is bowed outwardly and is engaged with the loops 4 at 6, 30 said bowed wire 5 resting upon the lobes 3. The purpose of this bowed wire 5 is that of supporting or distending the bust part of the vest, jacket or coat, which latter is intended to be buttoned so that it will retain its shape when on the garment hanger.

35 The hat support is made from a single piece of wire which is formed into a circle or ring 7, twisted at 8, and diverged laterally and provided with legs 9, each of which has three coils 10, 11 and 12, the latter encircling the wire 1 adjacent the inner ends of the lobes 3 and on opposite sides of the loop 2. This arrangement prevents any substantially relative lateral displacement of the hat support and the coat hanger.

40 The numeral 13 designates a supporting bracket, of general angular construction, having a loop 14, which may be passed over a screw or nail on the wall, door or other object from which the device is to be hung, while the lateral parts of the bracket are loosely engaged with the loops 10.

45 The numeral 15 designates a hook, from which an overcoat may be suspended, which has its ends hooked through the loops 11, and as this hook has its lateral parts disposed in front of the eye or coil 2, the said parts engage when the coat, vest or jacket is on its support.

50 The trousers holder consists of a piece of spring steel 16 faced with wooden strips 17 and equipped with

handles 18, one of which is provided with a hook 19 that is engaged with the eye 2.

A modification of the trousers hanger is shown in Fig. 3, where 20 and 21 represent wooden strips provided with spring hinges 22 and having handles 23, one of which has a link 24 of such length that when it is slipped over the other handle 23, the strips 20 and 21 are held open. One of the handles 23 has a hook 25 which may be engaged with an eye 2.

65

The manner in which the coat, vest or jacket will be hung on its hanger is obvious. When a hat is placed on the holder therefor, the holder is brought to an inclined position, but the hanging of a garment on its supporter will cause the hat supporter to raise up 70 again and hold the hat firmly against the wall or door to which the device may be attached. The trousers can be readily secured in the trousers holder or removed therefrom, as set forth heretofore.

Having thus described my invention, what I claim 75 as new and desire to secure by Letters Patent, is:—

1. In a garment hanger, the combination with a coat, vest or jacket hanger, of a hat support pivoted thereto to swing forwardly of the hanger, and a bracket pivoted to the hat support and adapted for sustaining the garment 80 hanger.

2. In a garment hanger, the combination with a coat, vest or jacket support, of a member pivoted to said support, parts carried by the said member and said support which are adapted to abut each other when the support and member are in certain positions, and attaching means for the said member, whereby the garment hanger may be supported from an object.

25 3. In a garment hanger, the combination with a coat, vest or jacket support, of a member pivoted thereto, 85 means connected to the member for attaching the garment hanger to a support, and a hook having lateral parts connected to the member which are adapted to engage the coat support when the parts of the garment hanger are in a certain position.

4. A garment hanger composed of a coat, vest or jacket support, a hat support having parts pivoted to the coat support, a bracket pivoted to the hat support, a hook connected to the hat support and adapted to abut the coat support when the parts are in a certain position, and 90 a bowed member connected to the coat support and adapted for distending the bust of the coat.

5. A garment hanger, consisting of a wire coat, vest or jacket support, a bowed wire connected thereto and adapted for distending the bust of the coat, vest or jacket, 95 a wire hat support having legs each provided with two loops or eyes and also loosely looped around the coat support, a hook having members which are looped through two of the eyes aforesaid, said hook being adapted to abut the coat support when in a certain position, and a 100 wire bracket pivotally engaged with the remaining loops or eyes of the hat support.

6. A garment hanger, consisting of a wire coat, vest or jacket support, a bowed wire connected thereto and adapted for distending the bust of the coat, vest or jacket, 105 a wire hat support having legs each provided with two loops or eyes and also loosely looped around the coat support, a hook having members which are looped through two of the eyes aforesaid, said hook being adapted to abut the coat support when in a certain position, a wire 110 bracket pivotally engaged with the remaining loops or eyes of the hat support.

115

bracket pivotally engaged with the remaining loops or eyes of the hat support, said coat support being formed into an eye adapted to abut the hook aforesaid, and a trouser hanger connected to said eye.

- 5 7. In a garment hanger, a coat, vest or jacket support made of wire, formed into lobes and bent into loops or eyes at the rear part thereof, a bowed wire having its ends loosely engaged with said loops or eyes so that it may be folded at right angles to the coat support or made

to rest on the lobes to extend in a lateral direction and 10 in the same general lateral plane as that of the coat support.

In testimony whereof, I hereunto affix my signature in presence of two witnesses.

JOHN SCHOLL.
